JEWELRY BOX

Jerome Schiffman, 128 Cartage Road, Scarsdale, N.Y.

Filed Dec. 4, 1964, Ser. No. 82,916

Term of patent 7 years

(Cl. D58—12.7)

FIG. 1

FIG. 2

FIG. 3

FIG. 4

I claim:

The ornamental design for a jewelry box, as shown.
